JOSEPH GOULDBOURN AND WILFRID THOMAS MINETT, OF LEICESTER, ENGLAND,
ASSIGNORS TO UNITED SHOE MACHINERY CORPORATION, OF PATERSON, NEW JER-
SEY, A CORPORATION OF NEW JERSEY

WELT GROOVING AND BEVELING MACHINE

Application filed June 11, 1927, Serial No. 198,239, and in Great Britain July 2, 1926.

This invention relates to welt grooving and beveling machines of the type generally employed in connection with the preparation of welting for use in Goodyear welt shoes and is herein shown as embodied in a machine of the same general character as that disclosed in a co-pending application, Serial No. 65,678, filed October 29, 1925, in the name of W. T. Minett, who is also one of the present applicants.

A machine organized as set forth in the application above referred to is adapted to reduce a strip of welting to substantially uniform thickness, to form a groove in the flesh side of the strip, and to form a beveled edge at the grain side of the strip. For these purposes, such machines are provided with three feed rolls comprising a work supporting roll, a presser roll located above the supporting roll and arranged to co-operate with the latter to feed the welting strip to the reducing means, and a roll which is located beside the supporting roll and which co-operates therewith to feed the reduced strip to the grooving and beveling instrumentalities.

One object of the present invention is to improve machines of this type the better to adapt them to feed and operate upon welting strips of different thickness, as well as upon a welting strip which varies substantially in thickness throughout its length.

With this object in view, and in accordance with one feature of the invention, the illustrated machine for operating upon welting strips comprises a work supporting roll, two feed rolls arranged to co-operate with the work supporting roll, supports for said feed rolls capable of being adjusted to provide two feeding stations of variable gap between the work supporting roll and said feed rolls, and connections between said supports constructed and arranged to transmit adjustments from one to the other for the purpose of facilitating the feeding of the work through the machine. Thus the invention provides a machine in which adjustments imparted to one of the feed rolls are imparted automatically to the other of said rolls. In the illustrated machine a reducing or evening knife is associated with one of the feed rolls

above referred to and arranged for adjustment in unison therewith and a grooving knife is connected with the other feed roll in such a manner that when the said feed roll is adjusted, a proportionate adjustment will be imparted to the grooving knife. The illustrated reducing knife and the associated feed roll are capable of being adjusted in unison manually, in accordance with the thickness to which it is desired to reduce the work, and of adjusting themselves to a limited extent in response to variations in the thickness of the work as it is fed into the machine, and the construction and arrangement is such that adjustment of the grooving knife and its feed roll is effected by adjustment of the other feed roll and the reducing knife, the adjustments of the two feed rolls being similar and the adjustment of the grooving knife being such that the depth of the groove formed by the knife will vary by substantially one-third of the increase or decrease in the thickness of the strip. As shown, an indicator is provided to facilitate manual setting of the reducing knife and its associated feed roll.

The invention further consists in features of construction and combinations and arrangements of parts hereinafter described and claimed.

The invention will be explained with reference to the accompanying drawings, in which—

Fig. 1 is a view partly in front elevation and partly in section, of an illustrative machine embodying the present invention;

Fig. 2 is a detail view in side elevation of certain parts shown in Fig. 1;

Fig. 3 is a view in elevation of the left-hand side of the machine viewed from the left of the position shown in Fig. 1;

Fig. 4 is an enlarged detail view partly in section showing the position of various feed rolls relatively to evening, grooving, and beveling knives; and

Fig. 5 is a view in elevation of the right-hand side of the machine, portions of the frame being broken away.

The illustrated embodiment of the invention comprises a frame 10 in which there is 100

5 rotatably mounted a driving shaft 12 having on its rear end fast and loose pulleys 14, 16, by means of which the shaft may be driven. The driving shaft 12 has mounted upon its forward end a knurled work-supporting roll 18 which, by means of a key and slot arrangement 19, may be slidably adjusted along the driving shaft 12. As shown in Figs. 4 and 5, the work supporting roll 10 18 has in its periphery a groove 20 which is adapted to receive a hook-shaped bearing plate 22 the upper outer edge of which bearing plate is shaped to conform to the outer diameter of the supporting roll 18, thereby 15 providing an uninterrupted supporting surface across the upper portion of the roll, notwithstanding the presence therein of the groove 20. The hooked extremity of the bearing plate 22 extends downwardly to a little 20 below a horizontal plane passing through the axis of the roll 18 and is cut away at 24 to form a straight edge which slopes slightly from the outer edge of the bearing upwardly to the inner edge thereof. At the side of the 25 roll 18 opposite the hooked end, the bearing plate 22 is arranged to extend downwardly and is fixed to a bracket 26 formed on the forward end of a shaft 28 (Fig. 5) which is slidably mounted in the machine frame 10. The shaft 28 is provided with a key 29, sliding in a keyway 31 formed in the frame 10, to prevent rotation of said shaft. The bracket 26 has rotatably mounted in it a screw 30 extending parallel to the shaft and threaded 35 into the machine frame 10. The screw 30 is prevented from moving lengthwise in the bracket and is equipped at its forward end with a hand wheel 32 by means of which it may be rotated to adjust the work-supporting roll 18, the bracket 26 and the bearing plate 22 toward or away from the machine frame and thus to adjust a member carried by the bracket 26 for a purpose to be herein-after explained. A hand screw 34 (Fig. 1) is 40 threaded into the frame 10 and bears against the shaft 28 to lock the latter in a desired position of adjustment.

45 Mounted closely in co-operative relation with the work-supporting roll 18 is a knife 40 (Fig. 4) having a straight cutting edge which is arranged to bevel the welting strip W, on the side of the strip that engages the surface of the work-supporting roll, immediately after the strip has been fed across said roll. The beveling knife 40 is mounted for vertical adjustment relatively to the work-supporting roll 18 and to this end, as shown in Fig. 4, the knife 40 is secured to the upper end of a spindle 36 adjustably seated 50 in the bracket 26. A screw 38 is threaded into the bracket 26 beneath the spindle 36 and may be adjusted vertically to impart corresponding uniform adjustment to the beveling knife 40. As shown in Fig. 4, the beveling knife is mounted at an angle to the ver-

tical, and when properly positioned for the cutting operation will lie with a considerable portion of its cutting extremity located within the groove 20 and out of the path of feed of the strip W, thereby reducing to a minimum any tendency on the part of the strip to lag or buckle by reason of frictional engagement as it is being fed past the beveling knife. 70

Furthermore, by reason of the fact that both the beveling knife 40 and the bearing plate 22 are carried by the bracket 26, it is apparent that the adjustment of the bracket laterally of the machine frame 10 adjusts also the knife 40 transversely of the direction of feed of the welting strip to locate the knife in such a position relatively to the strip as will produce a bevel of a desired width. 75

To co-operate with the work-supporting roll 18 in feeding the strip of welting through the machine, there is located above the work supporting roll a yieldingly mounted presser roll 42 having small teeth on its periphery. This presser roll is fixed on the forward end of a shaft 44 extending parallel to the shaft 12 and is driven by means of gears 46, 48 from the shaft 12 so that the two rolls 18 and 42 are driven at the same peripheral speed. The shaft 44 is rotatably mounted in a presser roll support 50 (Figs. 1 and 5) which is pivoted on a horizontal shaft 52 (Fig. 1) extending parallel to the two shafts 12, 44. The shaft 52 is mounted in an adjustable frame 54 having a dovetailed guideway 56 (Fig. 3) arranged to receive a wedge-shaped guide 58 formed on the machine frame 10. The presser roll 42 is urged yieldingly toward the work supporting roll 18 by means of a spring 60 (Fig. 1) surrounding a rod 62 carried by the adjustable frame 54. The rod bears at its lower end on the presser roll support 50 and its upper end is guided in a sleeve 64 which is threaded into an arm 65 projecting from the adjustable frame 54. The spring 60 bears against a collar 66 on the rod and against the lower end of the sleeve 64 so that by adjusting the sleeve within the arm 65 the compression of the spring may be likewise adjusted. 100

105 The presser roll carrying member 50 has an upwardly projecting arm 68 (Fig. 1) through which is threaded a screw 70 which bears against an abutment 71 formed on the adjustable frame 54 and limits downward movement of the presser roll 42 under the influence of its spring 60. The adjusting screw 70 may be locked in a desired position of adjustment 110 by means of a locking screw 72 located in the arm 68. The lower portion of the adjustable frame 54 is arranged to carry a horizontally extending evening knife 74 having its cutting edge positioned against a stop 76 laterally offset from the evening roll 42 and mounted on a block on the adjustable frame 54. 115

120 In order that the adjustable frame 54, and with it the presser roll 42 and the evening knife 74, may be adjusted toward or from the 125 130

work supporting roll 18 according to the thickness to which it is desired to even the work, the frame 54 has rotatably mounted in it near its upper end a hand screw 78 which at its lower extremity is threaded into the machine frame 10. The screw 78 is rotatably mounted in a block 80 fixed to the adjustable frame 54 and the screw has formed on it a collar 82 below the block 80 and a hand wheel 84 above the block. A flanged collar 86 is loosely mounted on the screw between the hand wheel and the block 80 and a spring 88 compressed between the hand wheel and the flange on the collar presses the adjustable frame downwardly. The distance between the lower face of the hand wheel 84 and the upper face of the block 80 is slightly greater than the thickness of the flanged collar 86. The compression spring 88 holds the collar down against the block 80 and this spring is somewhat weaker than the spring 60 which presses down the evening roll.

To facilitate the operator in adjusting the evening knife and the roll to even the work to the desired thickness, an indicator is provided which comprises a bell crank lever 90 pivoted to a plate 92 which is fixed on the frame 10 of the machine. One arm of the bell crank lever has the formation of a pointer and is arranged to swing over indicating marks 94 formed on the plate. The other arm of the bell crank lever is slotted and straddles a pin 96 fixed in the block 80. Thus vertical movement of the adjustable frame 54 and the block carrying the pin 96 causes the bell crank lever 90 to swing, thus indicating the magnitude of adjustment of the frame.

As already pointed out, the construction and arrangement of the parts of the machine are such that by adjusting the screw 78 the position of the presser roll heightwise of the work supporting roll may be varied. In the operation of the machine, when a welting strip W is presented to the work supporting and presser rolls, the presser roll 42 and the evening knife 74 are raised together against the action of the light spring 88 until the flanged collar 86 engages the under side of the hand wheel 84 which determines the thickness to which the welting strip is to be evened. Thereafter the presser roll may be further raised against the action of the strong spring 60 to allow for greater increases in the thickness of the welting strip, and, as above pointed out, during this further movement the knife 74 is fixed against further upward movement by means of the collar 86 engaging the hand wheel 84. The presser roll 42 and the knife 74 are normally set down close to the supporting roll 18 with the lowermost portion of the presser roll slightly below the knife edge so that if a portion of the strip W is thinner than the thickness to which the strip is to be evened and for which the hand

wheel 84 has been set, such thin portion will be fed by the presser roll under the pressure of the light spring 88 without being evened; the evening commencing only after the collar 86 engages the hand wheel 84.

In order to maintain proper clearance between the work supporting roll 18 and the knife 40 behind the edge of the knife, as the knife is raised, the slide 58 along which the adjustable frame 54 moves, has been arranged at an angle to the vertical so that as the knife is raised it also moves away from the work supporting roll.

At the left of the work supporting roll, as viewed from the front in Figs. 1 and 4, a feed roll 98, having small teeth formed on its periphery, is fixed to the forward end of a shaft 100 extending rearwardly of the machine parallel to the work-supporting roll shaft 12. The feed roll 98 is driven at the same peripheral speed as the work supporting roll by means of a gear 102 at the end of the shaft which meshes with the gear 46 on the work-supporting roll shaft. The feed roll shaft 100 is rotatably mounted in a feed roll frame or support 104 which is pivotally and slidably mounted on a horizontally rearwardly extending shaft 106 fixed in the frame 10 of the machine (Fig. 3). The feed roll frame 104 is formed near its upper end with a pair of lugs 108 which are held in abutting and interconnecting engagement with depending lugs 110 formed on the adjustable frame 54 by means of a spring 112 (Fig. 1) surrounding a rod 114 pivotally connected to the feed roll frame. The rod passes through a web 116 on the machine frame 10 between which and an adjustable hand nut 118 on the end of the rod, the spring is confined. The interengaging faces on the lugs 108, 110 (Figs. 1 and 3) are so arranged that when the adjustable frame 54 is moved along the slide-way 58 by the adjusting screw 84 or by variations in the thickness of the welting strip, the feed roll frame or support 104 is swung about its pivot shaft 106 and the arrangement is such that the presser roll 42 and the feed roll 98 are moved the same distance toward or away from the roll 18.

By reason of providing the above-described interconnections between the adjustable frame 54 and the feed roll frame 104 it will be understood that in the initial setting of the machine to produce a finished welting strip of a desired thickness, the size of the gap between the feed roll 98 and the work supporting roll 18 will vary directly in equal proportion to the size of the gap between the presser roll 42 and the work supporting roll 18. The size of the first-named gap is likewise dependent upon the setting of the evening knife 74 (by means of the hand wheel 84) relatively to the work supporting roll 18.

After the machine has been set to produce a welting strip of desired thickness and the

operation of the machine has commenced, the adjustable frame 54 is (by means of the hand wheel 84 engaging the collar 86) held against further upward movement. Since the frame cannot move upwardly, it follows that the lugs 110 carried by the frame cannot move to the left, as viewed from the position shown in Fig. 1, and, consequently, the feed roll 98 is by means of the spring 112, held against further movement in a direction away from the roll 18, thereby insuring that the evened welting strip, to the thickness of which the rolls 18 and 98 have been adjusted, will be fed firmly between said rolls.

Fixed at the front of the feed roll support or frame 104 is a vertical bearing 126 (Figs. 1 and 4), (similar in function to the bearing plate hereinbefore described as being positioned in the groove 20 in the work supporting roll 18) which surrounds the shaft 100 and has the upper portion of its edge shaped to conform to the periphery of the feed roll 98, thereby forming a continuous work-supporting surface across the upper and forward portion of that roll. The forward portion of the bearing 126 is cut away at about the level of a horizontal plane passing through the axis of the feed roll, as shown in Fig. 4, so as to form a straight edge 128 below which is located a grooving knife 132.

As shown in Fig. 3, the feed roll 98 is comprised of a main body portion and a collar 130 having a knurled periphery of the same diameter of the feed roll to support the front edge of the welting strip W. The bearing plate 126 is slightly thicker than the grooving knife 132 and, if it is desired to change the width of groove and, therefore, the thickness of the grooving knife, the collar 130 at the front of the plate may be repositioned to enable a thicker or a thinner bearing plate to be employed.

The provision of the peripheral groove in the work supporting roll 18, and the groove between the main body portion of the feed roll 98 and the collar portion 130, enables the beveling knife 40 and the grooving knife 132 to be positioned partially within the rolls, and immediately adjacent to the bite of the rolls without interfering in any respect with the feeding action of the machine. Also the bearing plates 126, 22 afford a firm backing for the strip as it is being fed, and provide a continuous and uninterrupted surface across the portions of rolls 18, 98 that come into engagement with the strip.

The mechanism for operating the grooving knife 132 of the illustrated machine is controlled by the variations in thickness of the strip of welting in such a manner that the grooving knife is caused to effect the grooving of the welting to a depth that varies by a pre-determined fraction of the variations in thickness of the welting. That is, if the thickness

increases, the depth of the groove increases but to a less degree, and if the thickness decreases the depth of the groove decreases but also to a less degree. To effect the desired grooving of the welting strip, the grooving knife 132 is fixed in an arm 134 (Fig. 1) pivotally and slidably mounted on a horizontal rearwardly extending shaft 136 which is fixed in the machine frame 10. The grooving knife arm 134 has in it a slot which straddles a stud 137 fixed in the grooving roll frame 104 and in the illustrated embodiment of the invention, the arrangement is such that, as the grooving roll is moved toward or away from the work supporting roll, the grooving knife is moved in the corresponding direction substantially two-thirds of that distance. Thus the depth of the groove varies by $\frac{1}{3}$ of the variations in the thickness of the strip. The stud in the grooving roll frame has mounted on it an eccentric bushing 138 which engages the slot in the grooving knife arm 134 so that by rotating the bushing the grooving knife edge may be set in any desired initial position of adjustment relatively to the point of the feed roll 98 nearest to the work supporting roll 18. This arrangement permits the grooving knife to be adjusted at the outset to produce a groove of a desired depth and thereafter the depth will vary in accordance with variations in the thickness of the strip, as before pointed out. The portion of the grooving knife arm 134 which has in it the slot fits between a face on the grooving roll frame and a collar 140 formed on the bushing by means of which the bushing may be rotated to effect the indicated adjustment.

The grooving knife 132 and its supporting arm 134 may be adjusted transversely of the direction of feed of the welting strip W to form the groove at any desired distance from the edge of the strip and to this end the feed roll frame 104, as shown in Fig. 3, is provided with a notch 120 within which there is located a collar 122 fixed to a hand screw 124. The hand screw 124 is threaded into the machine frame 10 and rotation of the screw imparts lateral bodily movement to the frame 104 and also to the grooving knife arm 134 which is mounted for free sliding movement along the shaft 136 (Fig. 1).

In the operation of machines of this character, it is sometimes found that the unevened welting strip is at various localities along its length of a thickness less than that for which the splitting knife 74, and the rolls 18, 42 and 98 have been set, and in an above paragraph it was explained that the space between the hand wheel 84 and the collar 86 was for the purpose of permitting the presser roll 42 to move downwardly under the action of the light spring 88, thereby decreasing the gap between the presser roll and the work supporting roll to feed between the rolls thin portions of the strip. As such portions are

being fed, the evening knife 74 occupies an inoperative position and the strip is fed along beneath it. Notwithstanding the undersized thickness of the strip at such localities, it is necessary to groove and bevel the strip throughout its entire length and to accomplish this, the strip must at all times, irrespective of thickness, be fed past the grooving and beveling knives in a firm and unyielding manner. Accordingly, the feed roll 98 is mounted in such a manner that it may be moved toward and from the work supporting roll 18 to feed the strip irrespective of variations in the thickness of the strip. It has been pointed out that, upon a thin portion of the strip passing between the presser roll 42 and the work supporting roll 18, the adjustable frame 54 will move downwardly under the influence of the light spring 88, and it follows that the lugs 110 carried by the frame 54 will move to the right of the position shown in Fig. 1. This movement of the lugs 110 allows the feed roll frame 104 carrying the lugs 108 to move to the right towards the work supporting roll 18 to decrease the feed gap between the two rolls 98 and 18, thereby feeding firmly the thinned portion of the strip. When the feed roll frame 104 moves thus, the grooving knife 132 moves two-thirds of the distance to decrease the depth of the groove by one-third of the decrease in thickness of the strip.

To assist in feeding the welt strip W through the machine and across the peripheries of the above-described feeding rolls, there are provided certain gaging devices which will next be described. The welt strip is fed to the evening rolls along a support 142 at the right of the machine and passes 40 down, after the evening operation, over the work supporting roll 18 and between that roll and the grooving feed roll 98 where it is first grooved and then beveled. The support 142 has at the front of it a fixed edge guide 144 and has on it an adjustable and yielding edge guide 146 (Figs. 4 and 5) between which guides the strip passes to the evening rolls. The edge guides are both carried down as close as possible to the bite of the work supporting and grooving rolls and the fixed 50 guide is cut away so as to permit of the axial adjustment of the work supporting roll 18. The adjustable guide 146 is fixed or formed on the forward end of a rearwardly extending rod 148 which is slidable in the machine frame. The rod near its rear end is reduced in diameter and has on it a spring 150 (Fig. 5) which is confined between the shoulder 152 formed by the reduction and a block 154 55 slidingly mounted on the reduced portion 156 and limited in its rearward movement by a nut 158 and a lock nut 160 on the end of the reduced portion 156. The block has on its upper face rack teeth 162 which are engaged 60 by a pinion 164 formed on the inner end of

a horizontal shaft 166 (Fig. 1) extending towards the right-hand side of the machine. The outer end of the shaft has fixed to it a hand lever 168 by which the pinion 164 may be rotated to move the block 154 and guide 70 146 forwardly or rearwardly of the machine towards or from the fixed guide 144 while allowing the adjustable guide to yield from any position. The hand lever moves over an arcuate plate 170 fixed to the machine frame 75 and has in it a spring clamp 172, engaging the edge of the plate, which locks the hand lever in adjusted position, there being indicating marks on the plate and a pointer on the hand lever to indicate the distance apart 80 of the guides.

To deflect the leading end of the welt strip downwardly after it leaves the evening rolls, there is provided a tapered finger 180 (Fig. 4) the thin end of which is held yieldingly up 85 against the under side of the knife. Stripper fingers 182 are provided to loosen the scrap welting from the presser roll 42, and a plate 184 carried by an arm of the machine frame 10 provides a guideway for carrying 90 the scrap material away from the working instrumentalities of the machine.

While the illustrated embodiment of the invention has incorporated in it evening, grooving and beveling knives, it is to be recognized that any one of the knives might be used alone or any two might be used in combination, as may be desired, without in any respect departing from the invention.

Having described the invention, what I 100 claim as new and desire to secure by Letters Patent of the United States is:—

1. In a machine of the class described, a work-supporting roll and a plurality of co-operating feed rolls, said feed rolls being so constructed and arranged that adjustments imparted to one of said rolls relatively to the work-supporting roll are transmitted automatically to the other of said rolls.

2. In a machine of the class described, a work-supporting roll for use in feeding a welting strip, a presser roll arranged to hold the strip in firm engagement with the work-supporting roll, a support for the presser roll, a feed roll arranged to co-operate with the work-supporting roll in feeding the welting strip past an operating instrumentality, a support for the feed roll, means for adjusting the position of the presser roll relatively to the work-supporting roll, and connections extending between the presser roll support and the feed roll support to transmit to the feed roll adjustments that are imparted to the presser roll.

3. In a machine of the class described, a work-supporting roll, two feed rolls located in co-operative relation with respect to the work-supporting roll, separate supports for said feed rolls, means to adjust one of said feed rolls relatively to the work-supporting

- roll, and connections between said feed roll supports to transmit adjustments from one feed roll to the other.
4. In a machine of the class described, a work-supporting roll, a presser roll located above said work-supporting roll, a feed roll located laterally of said work-supporting roll, separate supports for the presser and feed rolls, and connections extending between said supports so constructed and arranged that vertical adjustments imparted to said presser roll result in lateral adjustments of equal amounts being imparted to said feed roll.
5. In a machine of the class described a work-supporting roll and a feed roll arranged to co-operate in feeding a welting strip, an evening knife located in proximity to the bite of said rolls and arranged to reduce the welting strip to a substantially uniform thickness throughout its length, a second feed roll arranged to co-operate with the work supporting roll at a point spaced from the knife, a support for the second feed roll, means for adjusting the position of the evening knife relatively to the work supporting roll to produce an evened strip of a desired thickness, and connections between said evening knife and the support for the second feed roll constructed and arranged to transmit to said roll adjustments imparted to the evening knife.
6. In a machine of the class described, a work-supporting roll, a plurality of operating instrumentalities located at spaced intervals along the periphery of the work-supporting roll, and connections extending between said operating instrumentalities so constructed and arranged that movement imparted to one of said operating instrumentalities relatively to the work-supporting roll results in a movement being imparted to the other of said operating instrumentalities.
7. In a machine of the class described, a work-supporting roll, a plurality of adjustable operating instrumentalities located at spaced intervals along the periphery of the work-supporting roll, and connections between said operating instrumentalities so constructed and arranged that variation of adjustment of one of said operating instrumentalities relatively to the work-supporting roll in one direction results in a proportionate variation of adjustment of the other of said operating instrumentalities in a different direction.
8. In a machine of the class described, a work-supporting roll, an adjustable evening knife, means to adjust the position of the evening knife relatively to the work-supporting roll, an adjustable grooving knife, and connections extending between said evening knife and said grooving knife so constructed and arranged that variation of adjustment of said evening knife relatively to the work-supporting roll results in a predetermined fraction of said movement being imparted to said grooving knife relatively to the work-supporting roll.
9. In a machine of the class described, a work-supporting roll, a feed roll arranged to co-operate with said work-supporting roll, a presser roll also located in co-operative relation with said work-supporting roll, manually operable means for adjusting said presser roll relatively to said work-supporting roll, means automatically to impart corresponding adjustment to said feed roll, and means tending yieldingly to maintain such adjustment of the feed roll relatively to the work-supporting roll.
10. In a machine of the class described, the combination of a work-supporting roll, a presser roll located in proximity to the work-supporting roll, a support for the presser roll, a feed roll arranged to cooperate with the work-supporting roll at a point remote from the work-supporting roll, a support for the feed roll, and connections extending between said supports so constructed and arranged that when movement is imparted to the presser roll the feed roll will move with the presser roll an equal distance relatively to the work-supporting roll and will thereafter maintain a fixed position relatively to the work-supporting roll independently of continued movement of the presser roll in the same direction.
11. In a machine of the class described, the combination of a work-supporting roll, a presser roll located in proximity to the work-supporting roll, a grooving knife located in proximity to the work-supporting roll at a point remote from the presser roll, and connections extending between the presser roll and the grooving knife so constructed and arranged that when movement is imparted to the presser roll relatively to the work-supporting roll the grooving knife will move a predetermined fraction of such distance relatively to the work-supporting roll and thereafter maintain a fixed position independently of continued movement of the presser roll in the same direction.
12. In a machine of the class described, a work-supporting roll, a presser roll located in proximity to the work-supporting roll, a support for the presser roll, an evening knife located adjacent to the presser roll, a feed roll located in proximity to said work-supporting roll at a point removed from said presser roll, a support for said feed roll, a grooving knife located adjacent to the feed roll, and connections extending between the presser roll support, the evening knife, the feed roll support and the grooving knife so constructed and arranged that when movement is imparted to the presser roll and the evening knife the feed roll and the grooving knife will move with the presser roll a predetermined distance and thereafter maintain a fixed position relatively to the work-sup-

porting roll independently of continued movement of the presser roll in the same direction.

13. In a machine of the class described, a work-supporting roll, a presser roll arranged in co-operative relation with said work-supporting roll, an evening knife arranged to co-operate with said presser roll to reduce a welting strip to a desired thickness, said evening knife being so arranged relatively to the presser roll that it will cease to operate upon the welting strip when the thickness of said strip is less than the thickness it is desired to impart to the strip, a grooving knife arranged to operate upon the welting strip irrespective of variations in the thickness of the strip, one of said knives being adjustable, and connections between said knives for transmitting adjustment from one to the other.

14. In a machine of the class described, a work-supporting roll, a presser roll and a feed roll each arranged in co-operative relation with respect to said work-supporting roll, an evening knife associated with said presser roll, a grooving knife associated with the feed roll, means to adjust simultaneously the positions of said presser roll and said evening knife and of the feed roll and said grooving knife relatively to the work-supporting roll, and means for indicating visibly the extent of said adjustment.

15. In a machine of the class described, a work-supporting roll, two co-operating feed rolls spaced apart about the periphery of the work-supporting roll, a support for one of said feed rolls, a support for the other feed roll, means for adjusting one of said supports relatively to the other support, and connections extending between said supports to transmit adjustments from one feed roll to the other, means to adjust one feed roll, and means for indicating visibly the amount of said adjustment.

16. In a machine of the class described, a roll for use in feeding a welting strip, an operating instrumentality located within a groove formed within said roll, and a bearing member arranged substantially to fill the portion of said groove not occupied by said operating instrumentality.

17. In a machine of the class described, a roll for use in feeding a welting strip, an operating instrumentality located within a groove formed within said roll, and a bearing member having a portion of its peripheral contour coincident with the surface contour of said roll arranged substantially to fill the portion of said groove not occupied by said operating instrumentality.

18. In a machine of the class described, a plurality of co-operating rolls, grooves formed within the surface of said rolls, operating instrumentalities located within said grooves, and means also located in said grooves to co-operate with the surfaces of said

rolls located adjacent to said grooves to provide a continuous and uninterrupted feeding surface across the effective portions of said rolls.

19. In a machine of the class described, a work-supporting roll, a feed roll arranged to co-operate with said work-supporting roll in feeding a welting strip, grooves formed about the peripheries of said rolls, and a grooving and a beveling knife located one within each of said grooves immediately adjacent to the bite of said rolls.

20. In a machine of the class described, a work-supporting roll having a beveling knife associated therewith and extending within a groove formed therein, a feed roll having a grooving knife associated therewith and extending within a groove formed therein, means to impart lateral movement to the work-supporting roll and the beveling knife to adjust these members transversely of the direction of feed of a welting strip to impart to the strip a beveled edge of a desired width, and means to impart similar adjustment to the feed roll and grooving knife to impart to the strip a groove located at a desired distance from the edge of the strip.

21. In a machine of the class described, a work-supporting roll, a presser roll located in co-operative relation with respect to the work-supporting roll, a fixed edge gage, a yielding edge gage arranged to co-operate with said fixed gage in guiding a welting strip between said rolls, means including a rack and pinion for adjusting said yielding edge gage, and means to lock said rack and pinion to maintain said edge gage in a desired position of yielding adjustment.

22. In a machine of the class described, a plurality of co-operating rolls, a fixed edge gage, a yielding edge gage arranged to co-operate with said fixed gage, means to adjust the yielding edge gage relatively to said rolls, and means for indicating visibly the adjustment of said yielding gage relatively to said rolls.

23. In a machine of the class described, two feed rolls for feeding a welting strip having variations in thickness throughout its length, means tending to move one of said rolls toward the other, an adjustable stop for limiting said movement, means to operate upon said welting strip to form a groove therein the depth of which varies by a predetermined fraction of the increase or decrease in the thickness of the strip, and means controlled by the thickness of the strip for adjusting said stop.

24. In a machine of the class described, strip reducing means, means to bevel a strip along one edge thereof, adjustable means for feeding a strip to the reducing means, and means controlled by adjustment of said feeding means to form in a strip a groove the

depth of which varies systematically with variations in strip thickness.

25. In a machine of the class described, means for feeding a welting strip, an adjustable frame supporting the feeding means, means to bevel the welting strip along one edge thereof, and means controlled by adjustment of said frame for operating upon the welting to form therein a groove the depth of which varies systematically with variations in strip thickness.

26. In a machine of the class described, a work supporting roll, two feed rolls arranged to co-operate with the work supporting roll, 15 supports for said feed rolls capable of being adjusted to provide two feeding stations of variable gap between the work supporting roll and said feed rolls, and connections between said supports constructed and arranged 20 to transmit adjustments from one to the other.

27. In a machine of the class described, three feed rolls two of which are arranged to cooperate with the third at different locations about the periphery of the latter to afford two 25 feeding stations of variable gap, instrumentalities located at said feeding stations for operating upon a welting strip being fed therethrough, and means responsive to variations in thickness of the strip at one feeding station 30 for controlling the width of the variable gap at the other feeding station.

28. In a machine of the class described, three feed rolls two of which are arranged to co-operate with the third at different locations about the periphery of the latter to afford two feeding stations of variable gap, a knife spaced from a feed roll at one of said feeding stations for reducing the thickness of a strip of welting fed by said rolls, said knife 35 being capable of adjustment to vary the thickness of the strip, and connections between the knife and a feed roll located at the other feeding station for varying the width of the gap at the latter in proportion to the distance between the knife and the associated feed roll.

29. In a machine of the class described, three feed rolls two of which are arranged to co-operate with the third at different locations about the periphery of the latter to afford two feeding stations of variable gap, a knife spaced from a feed roll at one of said feeding stations for reducing the thickness of a strip of welting fed by said rolls, said knife 40 being capable of adjustment to vary the thickness of the strip, a grooving knife located at the other feeding station, and connections between said knives for adjusting the grooving knife to vary the depth of the groove in proportion to thickness of the strip.

60. In testimony whereof we have signed our names to this specification.

JOSEPH GOULDBOURN.
WILFRID THOMAS MINETT.
